UNITED STATES PATENT OFFICE.

ALEXANDER F. WINTERS, OF GRAND RAPIDS, MICHIGAN.

LATCH.

1,278,275.

Specification of Letters Patent. Patented Sept. 10, 1918.

Application filed January 9, 1918. Serial No. 210,972.

To all whom it may concern:

Be it known that I, ALEXANDER F. WINTERS, a citizen of the United States of America, residing at Grand Rapids, in the county 5 of Kent and State of Michigan, have invented certain new and useful Improvements in Latches; and I do hereby declare the following to be a full, clear, and exact description of the invention such as will enable others skilled in the art to which it 10 appertains to make and use the same.

This invention relates to a latch which is adapted for use with doors, blinds, or other structures of similar character which are 15 hinged to swing to open and closed positions. It is a primary object and purpose of the present invention to produce a simple and effective latch for attachment to a door which acts automatically as the door is 20 moved to closing position to engage with a suitable coöperating striker connected to the door casing or jamb to hold the door in closed position. My invention comprises various novel features of construction and 25 arrangement of parts for producing a particularly effective latch of this character and one which can be produced at a very low cost of manufacture, substantially all parts thereof being formed from metal stampings.

30 For an understanding of the invention reference may be had to the accompanying drawing showing a preferred embodiment thereof, in which

35 Figure 1 is a side elevation showing the latch and striker mounted, respectively, on a door and casing therefor, the door being in closed position.

Fig. 2 is a front elevation of the construction shown in Fig. 1.

40 Fig. 3 is a view similar to Fig. 1 showing the position of the parts as the door approaches closed position.

Fig. 4 is a vertical section taken centrally through the latch, and

45 Fig. 5 is a perspective view of the operating handle of the latch.

Like reference characters refer to like parts in the different views of the drawing.

50 In the construction of the latch a sheet metal housing 1 is provided, it having upper and lower ears 2 through which screws or other suitable fastenings may be passed to attach the same to a door 3. A hollow cylindrical bolt 4 is rotatably mounted in the upper portion of the housing, extending across the same and projecting at one end

beyond the housing, at which end it is provided with two diverging arms 5 and 6, set at an angle to each other and with the free ends thereof spaced a distance apart. These 60 arms extend beyond the edge of the door and are adapted to coöperate with a striker 7 which is attached to the door casing or jamb 8. In practice the striker is bent from a strip of metal and includes an upwardly 65 extending hook portion 9 at its outer end.

A bar 10 passes transversely through the bolt 4 within the casing, its lower end being divided to form a downwardly extending lip 11 which inserts into the upper end 70 of a coil spring 12, the opposite end of which bears against the lower side of the housing 1 and is held in position by any suitable pin or lug 13 which is fastened to and projects upwardly from said housing. 75 The line of force of the spring is adapted to pass across the pivotal axis of the bolt as the same is turned about its axis and in the position of the bolt and spring shown in Fig. 4, and also in dotted outline in Fig. 80 3, the upper end of the bar 10 strikes against an inwardly extending stop lug 14 pressed inwardly from the metal of the housing, thereby limiting the movement of the bolt 85 in the one direction.

Within the housing a rod is bent into U-shaped form, as indicated at 15, the free ends of the legs of the U being formed into outwardly projecting trunnions 16 and 17, which are rotatably mounted in opposite 90 sides of the housing 1. The trunnion 17 is extended a distance through the side of the housing and formed into a handle 18 which depends alongside of and below said housing.

When the door is open the parts are in the position indicated in Figs. 3 and 4. When the door is closed the inner side of the arm 6 strikes against the upturned hooked portion 9 of the keeper 7, causing 100 a rotation of the bolt 4 and a change of its position so that the line of force of the spring 12 passes across the pivotal axis of the bolt, whereupon the spring and the bar 10 assume the position shown in 105 dotted outline in Fig. 1, and the end of the arm 5 comes against the inner side of the hook 9. It is apparent that the spring in such case causes the arm 5 to bear against the inner side of the hook 9 and yieldingly 110 holds the door in closed position. To open the door the depending handle 18 may be

grasped and the same turned outwardly, whereupon the U-shaped part 15 bears against the lower end of the bar 10 turning the bolt and moving the spring to substantially the position shown in Figs. 3 and 4, the door opening readily when the bolt has been moved to such position.

A latch of the construction outlined is one which may be produced at a very low 10 cost of manufacture. All of the parts except the spring and handle may be produced by stamping and forming the same from sheet metal, and the handle is readily formed from a rod of small diameter. When 15 the door is closed it is automatically held by the latch in closed position and the same may be opened with a single outward movement imparted to the handle. It is also evident that the closing of the door is effected without in any manner moving the 20 handle which has no positive connection with any of the other moving parts of the latch. The latch is particularly of utility on small doors, such as are used on kitchen 25 cabinets and like articles of furniture, but may also be used with practically any type of door.

I claim:

1. In combination, a door and casing therefor, a housing attached to the door, a rotatably mounted bolt located transversely in and through the housing and having one end extended beyond the housing, two diverging arms at the end of the bolt, a striker 30 provided with an upturned outer end attached to the casing, said end being adapted to pass between the ends of said diverging arms, and a spring associated with the bolt, the line of force of which passes across the 35 rotative axis of the bolt as it is turned from one position to another, substantially as described.

2. A latch for doors comprising a housing, a bolt rotatably mounted in and passing 45 transversely through the casing, said bolt at one end extending laterally from the casing and formed with two angularly disposed and outwardly diverging arms, a spring associated with the bolt, the line of force of which 50 passes across the rotative axis of the bolt as it is turned from one position to another, and a handle for operating said bolt from one of its positions to the other, substantially as described.

3. A latch for doors comprising a housing, a bolt rotatably mounted transversely of and in the upper end of the housing, one end of the bolt extending laterally from the housing, keeper engaging means formed at said 60 end of the bolt, a bar located within the housing and passing through the bolt, a spring interposed between the lower end of the bar and the lower side of the housing, a rod formed with a U-shaped bend rotatably mounted within the housing, and a

handle at one end of the rod depending from the housing, said bend being adapted to engage the lower end of the bar to turn the bolt from one position to another, substantially as described.

70

4. A latch for doors comprising a housing, a bolt rotatably mounted transversely of and in the upper end of the housing, one end of the bolt extending laterally from the housing, keeper engaging devices at the end 75 of the bolt, a bar passing transversely through the bolt within the housing, a spring interposed between the lower end of the bar and the lower side of the housing, a stop in the upper part of the housing against which 80 the upper end of the bar engages in one position of the bolt, a handle rotatably mounted on and depending from the housing, and means within the housing connected to the handle adapted to engage with the lower 85 end of said bar to turn the bolt from one position to another on outward movement of the handle, substantially as described.

75

5. A latch for doors comprising a sheet metal housing, a hollow cylindrical bolt rotatably mounted and positioned horizontally in the upper end of the housing, one end of said bolt extending laterally from the housing, two angularly disposed diverging arms at the free end of the bolt, a bar extending 90 upwardly through the bolt within the housing, a spring interposed between the lower end of the bar and the lower side of the housing, a stop struck inwardly from the housing into the path of movement of the 95 upper end of the bar, a rod rotatably mounted between the sides of the housing and formed with an upwardly extending U-shaped bend adapted to engage against the lower end of the bar, and a handle depending from one end of the rod outside of the 100 housing, substantially as described.

90

6. In combination, a door and a casing therefor, a keeper formed with an upwardly turned outer end attached to the casing, a 110 latch attached to the door, said latch including a rotatably mounted horizontal bolt, one end of which is adapted to extend across the meeting edges of the door and casing, two downwardly extending diverging arms 115 at the end of the bolt, one of which is adapted to lie back of said upturned end of the keeper when the door is closed, and the other of which strikes against the front side of said upturned end of the keeper as the door is closed, thereby turning the bolt to its operative closing position, and means for yieldingly holding the bolt in either of two positions to which it may be turned.

115

7. In combination, a door and a casing 120 therefor, a keeper formed with an upwardly turned outer end attached to the casing, a latch attached to the door, said latch including a rotatably mounted horizontally located bolt, one end of which extends across 125 130

the meeting edges of the door and casing when the door is closed, two downwardly extending diverging arms at the end of the bolt, one of which in one position of the bolt lies back of said upturned end of the keeper when the door is closed, and the other of which strikes against the front side of said upturned end of the keeper as the door is closing and the bolt is in another position, 10 thereby turning the bolt to bring the first

arm back of the keeper, a spring associated with said bolt, the line of force of which passes across the rotative axis of the bolt to yieldingly hold the same in either position to which it is turned, and means to 15 manually turn the bolt to opening position when the door is closed, substantially as described.

In testimony whereof I affix my signature.
ALEXANDER F. WINTERS.
